UNITED STATES PATENT OFFICE

149,447

DESIGN FOR A MINIATURE AIRPLANE

Virgil W. Russell, Fort Worth, Tex.

Application June 28, 1946, Serial No. 131,151

Term of patent 7 years

(Cl. D34—15)

To all whom it may concern:

Be it known that I, Virgil W. Russell, a citizen of the United States, residing at Fort Worth, in the county of Tarrant and State of Texas, have invented a new, original, and ornamental Design for a Miniature Airplane, of which the following is a specification, reference being had to the accompanying drawings, forming a part thereof.

Figure 1 is a perspective view of a miniature airplane, showing my new design.

Figure 2 is a plan view of the miniature airplane shown in Figure 1.

Figure 3 is a front elevational view of my new design, and

Figure 4 is a side elevational view, also of my new design.

The wheels shown in Figure 1 have been omitted from Figures 2, 3, and 4.

I claim:

The ornamental design for a miniature airplane, substantially as shown.

VIRGIL W. RUSSELL.
